TOILET BOWL

Arthur A. Byerlein, Detroit, Mich.

Application June 22, 1935, Serial No. 27,866

7 Claims. (Cl. 4-6)

This invention relates to toilet bowls and the object of the invention is to provide a practical and convenient means for washing with wet toilet paper after the conventional use of dry paper.

In order to accomplish this, a toilet bowl is provided having a compartment on the side to allow free access between the compartment and the bowl, the compartment being shaped to allow water to flow from the compartment into the bowl.

Another object of the invention is to provide a toilet bowl in which the toilet seat is hinged mounted over the said compartment and the toilet seat hinge is arranged to support a roll of toilet paper.

A further object of the invention is to provide a toilet bowl of the character described in which the usual flushing means is provided and an auxiliary flushing means may also be provided at one side of the toilet bowl for flushing the compartment.

These objects and the several novel features of the invention are hereinafter more fully described and claimed and the preferred form of construction by which these objects are attained is shown in the accompanying drawing in which—

Fig. 1 is a perspective view of a toilet bowl embodying my invention.

Fig. 2 is an enlarged section taken on line 2—2 of Fig. 1.

As shown in Fig. 1, a toilet bowl 1 is provided which is of the usual porcelain construction and which is provided with a flush tank 2 operated by a flush valve handle 3. Formed integrally at one side of the bowl is a chamber 4 having a sloping bottom 5 and a vertical outer wall 6. This chamber is open to the interior of the bowl on one side to allow free access between the compartment and the bowl and a nozzle or jet 7 is supported in the wall 6 of the chamber 4 and is supplied with water through a water pipe 8 which is connected to the water supply pipe 9 for the flush tank 2. Flow through the pipe 8 is controlled by means of a manually operated valve handle 10 shown more particularly in Fig. 1 and the stem of which is shown in Fig. 2. By this arrangement, the valve handle 10 may be turned to one position to allow water to flow through the jet or nozzle 7 into the chamber 4 and by turning the valve handle in the opposite direction the water supply to the chamber 4 may be shut off. At the upper edge of the vertical wall 6, the compartment is provided with an outwardly extending flange 11. A pair of toilet paper

roll supports 12 are provided each having an end 13 extending through the flange 11 and having a nut 14 on the bottom by means of which the supports 12 may be firmly secured in vertical position. Each support 12 is provided at the upper end with a slot, as shown in Fig. 1, in which the toilet paper roll spindle is supported so that the roll 15 will readily turn in the supports. Each support 12 is also provided with an integral arm 16 and a bracket 17, shown more particularly in Fig. 1, is provided with upturned lugs 18 which are pivotally connected to the arms 16 by the pivot pins 19. This metal bracket 17 is provided with extending ends 20 and 21 and one portion 22 of the toilet seat is secured to the end 21 while the other portion 23 of the toilet seat is secured to the bracket 20. By this arrangement, the seat may be turned up sidewise on the pivot pins 19 to allow access to the interior of the bowl, if desired.

In use, the valve handle 10 may be turned to allow the water to flow from the nozzle 7 through the compartment 4 and over the edge 24 of the said compartment into the toilet bowl. The toilet paper may be torn off from the roll and wet at the nozzle 7 of the said compartment and may be used without dripping any water over any portion of the toilet seat due to the shape and design of the said seat in combination with the compartment 4 which allows free access between the compartment and the toilet bowl. The valve handle 10 may be turned, if desired, to allow a steady flow through the nozzle 7 into the compartment 4 or may be used for flushing the compartment and then turning the valve off. By the arrangement shown, the toilet paper is mounted at a convenient point in relation to the compartment 4 and by arranging the seat as shown, no water need be dripped over the seat as free access is allowed between the compartment and the bowl.

Having thus fully described my invention, its utility and mode of operation, what I claim and desire to secure by Letters Patent of the United States is—

1. The combination with a toilet bowl of a compartment formed integrally with the upper portion of the toilet bowl, said compartment being open on the side toward the toilet bowl and the upper edge of the compartment extending in the plane of the upper edge of the toilet bowl, manually operable means for producing flow of water in said compartment, the upper edge of the compartment being provided with a flange, a pair of supports secured to the flange, a toilet paper

- roll mounted in said supports, a toilet seat bracket pivotally connected to the aforesaid supports and a toilet seat secured to the toilet seat bracket, the toilet seat being provided with an open portion over the compartment allowing free access between the compartment and the bowl.
2. The combination with a toilet bowl of a compartment formed integrally with the upper portion of the bowl and opening into the bowl, independent flushing means for flushing the said compartment, said flushing means directing water into the compartment and through the open side thereof into the toilet bowl, a bracket pivotally mounted on the upper edge of the compartment and a toilet seat secured to said bracket, said toilet seat having an opening over the compartment to allow free access between the compartment and the bowl.
3. The combination with a toilet bowl provided with a flush tank of a compartment formed integrally with one side of the bowl and opening thereinto for the full width of the compartment, a nozzle discharging into the compartment, a toilet seat supported on the outer edge of the compartment and a toilet paper roll holder mounted on the outer edge of said compartment.
4. The combination with a toilet bowl provided with a flush tank of a compartment formed integrally with the bowl and opening thereinto, flushing means for flushing the said compartment, said flushing means allowing water to flow

through the compartment and through the open side thereof into the toilet bowl and a toilet seat pivotally mounted on the upper edge of said compartment.

5. The combination with a toilet bowl provided with a flush tank of a compartment formed integrally with one side of the bowl and opening thereinto for its full width and flushing means for flushing the said compartment, said flushing means allowing water to flow through the compartment and through the open side thereof into the toilet bowl.

6. The combination with a toilet bowl provided with a flush tank of a compartment formed integrally with one side of the bowl and opening thereinto for the full width of the compartment, a nozzle discharging into the compartment, a manually operable valve for controlling flow through said nozzle, said compartment being provided with a bottom sloping into the bowl.

7. The combination with a toilet bowl provided with a flush tank, of a compartment formed integrally with the bowl and opening thereinto, flushing means for flushing the said compartment, said flushing means allowing the water to flow through the compartment and through the open side thereof into the toilet bowl and a toilet seat pivotally mounted to rest on the upper edge of the toilet bowl.
